GAME DEVICE

Willard E. Andrews, Sycamore, Ill.

Application December 16, 1937, Serial No. 180,240

4 Claims. (Cl. 273—95)

My invention relates to game devices, and more particularly to those in which a token or disk is projected or dropped with the zone or place where it falls as speculative, and my main object is 5 to provide a device of this kind which provides fascinating entertainment.

A further object of the invention is to provide means which challenge the skill or luck of the player to attain a given goal.

10 Another object of the invention is to provide a field containing a miscellaneous array of values, and have the token or disk dropped through any chosen one of an array of passages at an elevation above the said field, the token falling according to the position and direction in which it is deposited in the chosen passage.

An additional object of the invention is to construct the field adapted to receive the token or disk in a series of units which are closely grouped, 20 but tilttable to cause the token or disk to slide off into a compartment below.

An important object of the invention is to design the novel game device along lines of simplicity and efficiency.

25 With the above objects in view and with any others that may suggest themselves from the description to follow, a better understanding of the invention may be had by reference to the accompanying drawing, in which:

30 Fig. 1 is a perspective view of the game device; Fig. 2 is a horizontal section;

Fig. 3 is an enlarged section on the line 3—3 of Fig. 1; and

35 Fig. 4 is an enlarged section on the line 4—4 of Fig. 2.

Games in which coins, tokens or other projectiles are tossed, dropped or deposited with a particular goal to be attained as governed by skill or chance have been devised from time to time, 40 but in most instances the projectile was freely thrown, and the apparatus was not of a portable or unitary character. I have therefore devised an apparatus which contains all the values of the game in one compact unit which may be placed 45 anywhere and is constituted along definite lines.

In accordance with the foregoing, the game device is essentially in the form of a cabinet 5, which may be square, as shown, or of any other suitable configuration. The sides of the cabinet 50 are preferably made with glass panels 6 to afford a clear view to the interior. The top of the cabinet is a thick wooden board 7 cut with a plurality of narrow slots 7a. While these may be arranged in any order, I prefer that they be in 55 four units, the slots in each unit being at right

angles in direction to those in the adjoining unit.

The cabinet 5 has a bottom 8 above which is a false bottom or platform composed of a series of strips 9 arranged in close succession. The strips 9 are, for the purpose of the game, considered as one general field or group, divided off into a large number of individual units of square form. As shown in Fig. 2, these units are marked with numbers from 1 to 10, the numbers being in mixed or arbitrary relation; or, the 10 squares may be marked with any other legend or characteristic which will suit one game or another.

To play the game, a token or disk, preferably of metal, is freely dropped through a chosen one of the slots 7a at such a point as is calculated by the player to cause the projectile to fall upon a chosen figure in the field below, the walls of the slots 7a being cut straight down so as to preclude any maneuver on the part of the player to train the token at an angle to attain the desired goal. The skill of the player therefore consists in first choosing the right slot, and second in determining the position in such slot most nearly in line with the goal. Necessarily, a speculative element enters into the travel of the token through the circumstance that the chosen slot is of much greater length than the diameter of the token and also that the token may swerve from a direct fall by turning in one or another direction during 20 the fall.

In order that the field of figures may be cleared of one or more tokens at any time it is considered or expedient, the strips 9 are pivoted endwise in the cabinet by means of spindles 9a, so as 25 to be tilttable, as indicated by the dotted lines in Fig. 4, and so cause the projectiles to slide off onto the cabinet bottom 8. In order that the strips may tilt in unison, their spindles are formed with downward stems 10 which are linked with 30 their lower ends to a horizontal rod 11. The latter extends through the side of the cabinet to terminate with a handle 11a, and when the latter is drawn outwardly the strips 9 are tilted 35 as previously described. However, the strips are 40 ordinarily retained in a horizontal position by draw-springs 12, to rest on stop pins 13 projecting from the side of the cabinet.

It is evident from the above description that I have provided a simple and compact apparatus for playing any kind of game where a token or disk is projected toward a speculative goal. The sides of the cabinet are almost entirely of glass, in order to make the path of the projectile and the field of the goal clearly visible from 45 50 55

all sides. The apparatus is of a nature for competitive skill between groups of players with scores to be kept as prescribed or as mutually arranged. Or, the device may be used for premium purposes where commodities are sold, by the presentation of one or more tokens with each purchase and the award of a suitable premium where a certain value or score is attained by the purchaser. Whatever type of game or contest is applied to the device, it is apparent that no difficulty or mystery attends the playing, since all parts in the apparatus that deal with the playing are clearly exposed. Also, the sectional field is quickly cleared of the projectiles by the simple expedient previously described.

While I have described the invention along specific lines, various minor changes and refinements may be made therein from time to time without departing from its principle, and I consider all such changes and refinements as coming within the scope and spirit of the appended claims.

I claim:

1. A game device comprising a field having a miscellaneous array of goal values, and a board at an elevation from said field, the board having a plurality of elongated spaced passages over said field for tokens dropped toward chosen ones of said values, said passages comprising vertical slots of a width for the slideable passage of the tokens and of a length substantially greater than the major dimension of the token, and said board being of a thickness sufficient to prevent devia-

tion of the token from a vertical plane while passing through the slots.

2. The structure of claim 1, said field being in a series of strips laterally-grouped in close succession, an enclosure for the field, trunnions extended endwise of the strips at points medially thereof and journaled in the enclosure to render the strips rockable, stops for the lateral portions of the strips at one side to seat the strips horizontally, and yieldable means to maintain the strips in the seated position. 5

3. The structure of claim 1, said field being in a series of strips laterally-grouped in close succession, an enclosure for the field, trunnions extended endwise of the strips at points medially thereof and journaled in the enclosure to render the strips rockable, stops for the lateral portions of the strips at one side to seat the strips horizontally, and draw-springs to maintain the strips 15 in the seated position.

4. The structure of claim 1, said field being in a series of strips laterally-grouped in close succession, an enclosure for the field, trunnions extended endwise of the strips at points medially thereof and journaled in the enclosure to render the strips rockable, stops for the lateral portions of the strips at one side to seat the strips horizontally, draw-springs to maintain the strips 25 in the seated position, a rod linked to the strips at the seated position, and a handle at one end of the 30 rod. 20

WILLARD E. ANDREWS.
